DES. 2458

Letters Patent, No. 2458, Dated Sept 2, 1866.

Design for a Snap Hook.

The Schedule referred to in these Letters Patent and making part of the same.

To all whom it may concern:

It is known that I, John Brody of Easton in the County of Northampton, State of Pennsylvania have invented a new and useful Design for Snap Hook, and I do hereby declare that the following is a full, clear, and exact description, which will enable others skilled in the art to understand the same, reference being had to the accompanying drawing forming a part of this Specification in which,

Figure 1, represents a side elevation of this invention.

Figure 2, is a back view of the same.

Similar letters of reference indicate like parts.

The distinguishing features of this design are the peculiar shape of the shank and also that of the hook.

The shank A, is broad and flat where it joins the ring B, and it gradually tapers off towards the ring hook C, giving to the whole the appearance of great strength and durability, as shown particularly in Fig. 2.

The hook C is formed with a peculiar curve as shown in Figure 1, of this drawing I claim as new and desire to secure by Letters Patent,

The Design for a Snap Hook as shown and described.

The above Specification of my invention signed by me this 24th day of July 1866
